Francis Lee Faries, INVENTOR

UNITED STATES PATENT OFFICE.

FRANCIS LEE FARIES, OF BELLWOOD, PENNSYLVANIA.

DESIGN FOR A BOUQUET-HOLDER FOR BICYCLES.

SPECIFICATION forming part of Design No. 28,162, dated January 11, 1898.

Application filed July 15, 1897. Serial No. 644,731. Term of patent 31 years.

To all whom it may concern:

Be it known that I, FRANCIS LEE FARIES, a citizen of the United States, residing at Bellwood, in the county of Blair and State of Pennsylvania, have invented and produced a new and original Design for a Bouquet-Holder for Bicycles, of which the following is a specification, reference being had to the accompanying drawing, forming a part thereof.

- 10 The leading or characteristic features of my design for a bouquet-holder comprise a female figure representing an angel clasping in her arms a vase, her arms being bare from the shoulders down and the figure clad in a
- 15 plain robe cut low in the breast and confined at the waist by a plain girdle which draws the robe close, thereby making folds in the dress, as shown in the drawing. The skirt falls in graceful lines, fitting the figure some-
- 20 what tightly at the front and hips and flow-

ing back to where it is joined by the tip of the wing. The vase, held in the arms and supported against the breast of the figure, is substantially of the shape of an ancient Assyrian jar, with the addition of a capital at the top, ²⁵ extending from the top about one-third of the distance to a bead, and thence to a flaring or bulbous portion, which is characterized by a bead below the same, whence it curves to the base and appears to rest upon an ornamental bracket. ³⁰

Having thus described my design for a bouquet-holder, what I claim is—

The design for a bouquet-holder, as herein shown and described.

FRANCIS LEE FARIES.
